UNITED STATES PATENT OFFICE.

MALVERN A. EATON, OF LITTLETON, NEW HAMPSHIRE, ASSIGNOR TO PIKE MANUFACTURING COMPANY, OF PIKE, NEW HAMPSHIRE, A CORPORATION OF NEW HAMPSHIRE.

MACHINE FOR SHAPING ARTICLES BY GRINDING.

1,377,118.

Specification of Letters Patent.

Patented May 3, 1921.

Application filed March 13, 1920. Serial No. 365,612.

To all whom it may concern:

Be it known that I, MALVERN A. EATON, a citizen of the United States, residing at Littleton, in the county of Grafton, State 5 of New Hampshire, have invented certain new and useful Improvements in Machines for Shaping Articles by Grinding, of which the following is a description, reference being had to the accompanying drawings, 10 forming a part hereof.

My invention relates to grinding machines for truing and finishing the ends of sharpening stones such as oil stones, whet stones and the like, and other articles, and has 15 for its object to provide a machine for this purpose which will be simple and comparatively inexpensive in construction and operation and will be effective to grind the ends of a considerable number of stones or other 20 articles at the same time. A further object of the invention is to provide simple and effective mechanism to reciprocate the stones or other articles across the face of the grinding means. A further object of the invention is to provide 25 means for regulating the pressure of the stones or other articles to be ground, against the grinding means. A further object of the invention is to provide means by which the stones or other articles to be ground may be conveniently inserted in and removed from the machine. 30

With the above described objects and other objects hereinafter described in view my invention consists in the construction 35 and combination of elements hereinafter described and claimed.

Referring to the drawings;

Figure 1 is a side elevation of a complete machine for grinding the ends of sharpening stones embodying my invention, 40

Fig. 2 is an end view of the machine shown in Fig. 1,

Fig. 3 is a fragmentary cross sectional view on line 3—3 of Fig. 1 on an enlarged 45 scale,

Fig. 4 is a fragmentary end view on an enlarged scale of the lower portion of the reciprocating work carrying means,

Fig. 5 is a plan view on an enlarged scale 50 of the holder for the stones to be ground, and

Fig. 6 is a horizontal sectional view on a reduced scale on line 6—6 of Fig. 1.

In the drawings 1 indicates a rotating

grinding disk preferably consisting of a 55 disk of cast iron supplied with sand or other finely divided abrasive material and water, by any convenient means. 2 indicates a cross beam preferably of I shape in cross section, supported by any convenient means 60 in fixed position above and in a plane parallel with the plane of the upper surface of the grinding disk 1. 3 indicates a holder for the stones to be ground. This holder for the stones to be ground consists, as 65 shown in detail in Fig. 5, of a rectangular frame divided into sections by cross bars 4, 4, and provided in its sides 6 and 7 with set screws 5. The side 6 is preferably provided at its ends with vertical rollers 8 70 which, in operation bear against a fixed bar 9 extending across but above and out of contact with the face of the grinding disk and serving to prevent the work holder from being carried around with the grinding 75 disk as it rotates. The stones or other articles to be ground 10 are clamped in the sections of the work holding frame by means of the set screws 5, a considerable number of the stones to be ground being thus held 80 assembled so as to be all ground at the same time.

In the operation of grinding the stones the work holder 3 is reciprocated in a radial direction across the face of the grinding disk 85 being held against being carried with the grinding disk in its rotation, by the fixed bar 9 as clearly shown in Fig. 6. The work holder is provided at its ends with trunnions 11 and 12 which are journaled respectively 90 in the lower ends of vertical arms 13 and 14, the upper ends of which embrace and are free to move vertically on the ends of a bar 15 preferably I shaped in cross section 95 and adjustably supported from the cross beam 2 as hereinafter described. As the weight of the work holder 3 with the stones carried by it and the arms 13 and 14, is or may be too great to permit the most effective operation of the grinding disk, this weight is arranged to be more or less counterbalanced. The means for this purpose comprises arms 16 and 17 pivoted at their outer ends to the vertical arms 13 and 14 respectively and connected between their ends by links 18 and 19 respectively, to the bar 15, the inner ends of the arms 16 and 17 extending beneath a weight 20 which rests 100 105

on them being guided by rods 21 and 22 extending downward from the bar 15, the weight by its pressure on the inner ends of the arms tending to raise the vertical arms 5 13 and 14, and with them the work holder 3. A lever 23 pivoted at 24 to the weight 20 and having one end connected by link 25 to vertical arm 13 and carrying on its other end an adjustable weight 26, serves 10 to regulate the pressure of the weight 20.

The bar 15 is supported near its ends by vertical screws 27 and 28 which engage screwthreads formed in the bar, and are swiveled at their upper ends in a bar 30 15 which is provided near its ends with brackets 31 and 32 in which are journaled pairs of rollers 33 and 34 which are adapted to travel on the lower flanges of the I beam 2. The vertical screws 27 and 28 are provided near 20 their upper ends with gears 35 and 36 which are in mesh with pinions 37 on stub shafts which carry gears 38 and 39 with which mesh bevel gears 40 and 41 carried by horizontal shaft 42 having at one end a hand wheel 43 25 for operating it. By rotating the hand wheel the screws 27 and 28 are rotated to raise or lower the bar 15.

Near its lower end the vertical arm 14 is provided with a shaft 44 on which is pivoted 30 a lever 45 provided on its under side with a notch 46 adapted to engage any one of a series of pins 47 carried by a swinging lever 48 pivoted at its upper end in a bracket 49 on the cross beam 2. Near its upper end this 35 swinging lever is provided with a slot 50 with which engages a pin 51 carried by a pitman 52 the other end of which is pivoted to a crank 54 on a shaft 55 journaled in a block 56 carried on the cross beam 2. On the 40 shaft 55 is a bevel gear 57 which is in mesh with a bevel pinion 58 on a shaft 59 which, by means of suitable gearing as shown, is arranged to be driven by a belt 60 from any 45 convenient source of power.

In order to keep the work holder 3 from turning on its trunnions 11 and 12 while the stones are being ground, holding arms 61 and 62 each having a notch 63 at its end are caused to engage the frame of the work 50 holder on opposite sides of the trunnion 12. These holding arms 61 and 62 are eccentrically mounted on the shaft 44 which is arranged to be rotated by hand wheel 64 and is locked against rotation by spring pawls 65.

In order to permit the stones to be inserted 55 in the work holder the lever 45 is raised to disengage its notch 46 from the pin 47 and is then swung down out of line with the swinging lever 48. The arms 14 and 13 and the parts connected with them are then moved to the right as shown in Fig. 1, until the arm 13 is clear of the grinding disk the 60 rollers 33 and 34 traveling on the lower flanges of the cross beam 2. When thus run back clear of the grinding disk, the hand 65

wheel 64 is rotated to withdraw the ends of arms 61 and 62 from engagement with the end of the frame of the work holder 3 and this work holder may then be rotated on its trunnions 11 and 12 to swing it to a vertical 70 position. The stones may then be packed into the sections of the work holder and secured therein by set screws 5. When the stones are all in place the work holder is swung to horizontal position and secured in 75 such position by engaging the notches 63 of the arms 61 and 62 with the end of the work holder frame, the shaft 44 being rotated to cause the arms to hold the frame in horizontal position. The work holder and the 80 parts connected with it is then run forward over the grinding disk and the lever 45 is brought up and its notch 46 is caused to engage one of the pins 47 of the swinging lever 48. The machine is then ready for operation. 85 In order to facilitate the movement of the work holder off from and onto the grinding disk the weighted end of the lever 23 may be depressed to lift the stones free of the surface 90 of the grinding disk.

In operation, after the work holder is in position, the lever 48 will be swung to and fro by the pitman 52 and, through the lever 45, will reciprocate the work holder on the surface of the grinding disk, the pressure of 95 the stones against the grinding disk being regulated by the weight 26. The screws 27 and 28 serve to adjust the height of the work holder and may be operated through the hand wheel 43 to gradually lower the work 100 holder as the stones carried by it are ground away.

While the machine shown and described is particularly designed and intended for use in grinding the ends of sharpening stones 105 which are rectangular in cross section, it is obvious that it may be used to grind the ends of sharpening stones of other shapes in cross section or to grind the sides or faces of such stones or the ends, sides or faces of other articles than sharpening stones which are adapted to be secured in a holder such as that described, and the invention is not intended to be limited to the particular use described. It should be understood that I do not desire 110 to be limited to the particular construction shown or described as it is obvious that such construction and the arrangement of the parts may be modified in many ways without departing from the spirit of the invention. 115

Having thus described my invention what I claim is:

1. In a machine for shaping articles by grinding, the combination of a grinding disk rotating in a horizontal plane, a fixed track above and parallel with the face of the grinding disk, a frame suspended from and movable on said fixed track, means for reciprocating the frame, a work holder carried by the frame adapted to hold the ar- 125 130

ticles to be ground in contact with the face of the grinding disk, and means carried by the frame for counterbalancing the weight of the work holder.

- 5 2. In a machine for shaping articles by
grinding, the combination of a grinding disk rotating in a horizontal plane, a fixed track above and parallel with the face of the grinding disk, a frame suspended from
10 and movable on said track comprising a horizontally arranged bar and arms suspended from and vertically movable on said bar, a work holder carried by said arms adapted to hold the articles to be ground in contact
15 with the face of the grinding disk, and means carried by said bar for counterbalancing the weight of the work holder.

3. In a machine for shaping articles by
grinding, the combination of a grinding disk rotating in a horizontal plane, a fixed track above and parallel with the face of the
20 grinding disk, a frame suspended from and movable on said track comprising a vertically adjustable horizontally arranged
25 bar and arms suspended from and vertically movable on said bar, means for reciprocating the frame, a work holder carried by
30 said arms adapted to hold the articles to be ground in contact with the face of the
35 grinding disk, and means carried by said bar for counterbalancing the weight of the work holder.

4. In a machine for shaping articles by
grinding, the combination of a grinding disk rotating in a horizontal plane, a fixed track above and parallel with the face of the
40 grinding disk, a frame suspended from and movable on said track comprising a horizontally arranged bar and arms suspended
45 from and vertically movable on said bar, means for reciprocating the frame detachably connected therewith, and a work holder having trunnions at its ends journaled in said arms and adapted to hold the articles to be ground in contact with the face of the
50 grinding disk.

5. In a machine for shaping articles by
grinding, the combination of a grinding disk rotating in a horizontal plane, a fixed track above and parallel with the face of the
55 grinding disk, a frame suspended from and movable on said track comprising a hori-

having trunnions at its ends journaled in
said arms, and means for holding the work
holder in horizontal position to hold the
articles to be ground in contact with the face
60 of the grinding disk.

6. In a machine for shaping articles by
grinding, the combination of a grinding disk rotating in a horizontal plane, a fixed track above and parallel with the face of the
65 grinding disk, a frame suspended from and movable on said track comprising a horizontally arranged bar and arms suspended from and vertically movable on said bar,
70 means for reciprocating the frame, a work holder carried by said arms adapted to hold the articles to be ground in contact with the face of the
75 grinding disk, and means for counterbalancing the weight of the work holder comprising levers pivoted at their ends to said arms, fulcrumed in links depending from said bar and having a weight bearing downward on their inner ends.

7. In a machine for shaping articles by
grinding, the combination of a grinding disk rotating in a horizontal plane, a fixed track above and parallel with the face of the
80 grinding disk, a frame suspended from and movable on said track comprising a horizontally arranged bar and arms sus-
85 pended from and vertically movable on said bar, means for reciprocating the frame, a work holder carried by said arms adapted to hold the articles to be ground in contact with the face of the
90 grinding disk, and means for counterbalancing the weight of the work holder comprising levers pivoted at their outer ends to said arms, fulcrumed in links depending from said bar and having a weight bearing downward on their inner ends and a lever pivotally connected at one
95 end to one of said arms, pivotally connected near its midlength with the weight and having a weight adjustably mounted on its free end.

In testimony whereof I affix my signature
this fourth day of March, 1920.

MALVERN A. EATON.

zontally arranged bar and arms suspended from and vertically movable on said bar, means for reciprocating the frame detachably connected therewith, a work holder having trunnions at its ends journaled in said arms, and means for holding the work holder in horizontal position to hold the articles to be ground in contact with the face of the grinding disk. 55 60

6. In a machine for shaping articles by grinding, the combination of a grinding disk rotating in a horizontal plane, a fixed track above and parallel with the face of the grinding disk, a frame suspended from and movable on said track comprising a horizontally arranged bar and arms suspended from and vertically movable on said bar, means for reciprocating the frame, a work holder carried by said arms adapted to hold the articles to be ground in contact with the face of the grinding disk, and means for counterbalancing the weight of the work holder comprising levers pivoted at their ends to said arms, fulcrumed in links depending from said bar and having a weight bearing downward on their inner ends. 65 70 75

7. In a machine for shaping articles by grinding, the combination of a grinding disk rotating in a horizontal plane, a fixed track above and parallel with the face of the grinding disk, a frame suspended from and movable on said track comprising a horizontally arranged bar and arms suspended from and vertically movable on said bar, means for reciprocating the frame, a work holder carried by said arms adapted to hold the articles to be ground in contact with the face of the grinding disk, and means for counterbalancing the weight of the work holder comprising levers pivoted at their outer ends to said arms, fulcrumed in links depending from said bar and having a weight bearing downward on their inner ends and a lever pivotally connected at one end to one of said arms, pivotally connected near its midlength with the weight and having a weight adjustably mounted on its free end.

In testimony whereof I affix my signature
this fourth day of March, 1920.

MALVERN A. EATON,
